(57) **CLAIM**

We claim the ornamental design for a laminated panel having interlocking edges, as shown and described.

DESCRIPTION

FIG. 1 is a perspective view of a laminated panel having interlocking edges; the portion of the Figure depicted in broken lines, which shows how a second panel may be connected to a first panel, is for illustrative purposes only and forms no part of the claimed design.

FIG. 2 is a front elevational view of the laminated panel, the rear being a mirror image thereof.

FIG. 3 is a left side elevational view of FIG. 2.

FIG. 4 is a right side elevational view of FIG. 2.

FIG. 5 is a top plan view of FIG. 2, the bottom plan view being a mirror image thereof; and,

FIG. 6 is a partial view of the right side of FIG. 5, which shows how a second panel, partially depicted by broken lines, may be connected to a first panel; the portion of the figure in broken lines is for illustrative purposes only and forms no part of the claimed design.

The laminated panel having interlocking edges is depicted broken in the center in FIGS. 1 through 4 to show indeterminate length.
